UNITED STATES PATENT OFFICE.

DANIEL J. ARPIN, OF GRAND RAPIDS, WISCONSIN.

RUT-CUTTER.

SPECIFICATION forming part of Letters Patent No. 430,361, dated June 17, 1890.

Application filed March 10, 1890. Serial No. 343,377. (No model.)

To all whom it may concern:

Be it known that I, DANIEL J. ARPIN, of Grand Rapids, in the county of Wood, and in the State of Wisconsin, have invented certain new and useful Improvements in Rut-Cutters; and I do hereby declare that the following is a full, clear, and exact description thereof.

My invention relates to rut-cutters for ice-roads; and it consists in certain peculiarities of construction and combination of parts, to be hereinafter described with reference to the accompanying drawings and subsequently claimed.

15 In the drawings, Figure 1 represents a side elevation of a portion of a sled-runner provided with a rut-cutter constructed according to my invention; Fig. 2, a longitudinal section; Fig. 3, a plan view, partly in horizontal 20 section; and Fig. 4, a transverse section with parts broken away.

Referring by letter to the drawings, A represents a sled-runner cut out to form a recess having an inclined rear face, against which 25 rests the transverse wall *b* of a shell *B*, the latter being of a form corresponding to the contour of the runner, to which it is fastened by screws or other suitable means, and in this connection attention is called to the fact 30 that my device may be used with either a round or flat runner, the shell being curved or angular in general contour, according to the shape of the runner it is to fit.

As shown, the main portion of the shell is 35 set in flush with the runner and has a wing *c* on the outside at right angles to said runner. Hinged to the wing *c* is a plate *d*, preferably turned up at its outer forward corner, and joined to said wing and rear portion of 40 the shell is a fender *e*, the latter being oblique to the sled-runner. A bolt *f* is passed through the transverse wall *b* of the shell to engage a longitudinal slot *g* in a knife *C*, the latter being adjustably held in place by a set-nut *h* 45 on the bolt *f*, as best illustrated in Fig. 2. The cutting end of the knife *C* extends through an opening *i* in the bottom of the shell *B*, and is preferably concave. While I have shown the knife as having its cut straight 50 across the line of draft, it is obvious that the device may be so constructed as to vary the angle of said knife, whereby the latter may have more or less of a shear cut.

In the operation of my device the knife is

adjusted to suit the depth of cut desired, and 55 the chips and dirt coming from said knife are prevented from falling back into the rut by means of the wing *c* on the shell *B* and hinged plate *d*, the latter being free to work up and down, according to the roughness of the surface over which it travels. This vibratory movement of the hinged plate causes the chips, &c., to shake off far enough away from the sled-runner to prevent their falling back into the rut before the fender *e* has an opportunity to throw them still farther out as said runner travels forward.

Having thus described my invention, what I claim as new, and desire to secure by Letters Patent, is—

1. A rut-cutter for attachment to a sled-runner, the same comprising a shell having a general contour corresponding to that of said runner, a transverse wall, and a right-angled wing, and a knife connected to said transverse wall to extend through the bottom of the shell, substantially as set forth.

2. A rut-cutter for attachment to a sled-runner, the same comprising a shell having a general contour corresponding to that of said runner, a transverse wall, a right-angled wing, and a plate hinged to the wing, and a knife connected to said transverse wall to extend through the bottom of the shell, substantially as set forth.

3. A rut-cutter for attachment to a sled-runner, the same comprising a shell having a general contour corresponding to that of said runner, a stationary transverse wall, and an oblique fender, and a knife connected to said transverse wall to extend through the bottom of the shell, substantially as set forth.

4. A rut-cutter for attachment to a sled-runner, the same comprising a shell having a general contour corresponding to that of said runner, a transverse wall, a right-angled wing, a plate hinged to the wing, and an oblique fender, and a knife connected to said transverse wall to extend through the bottom of the shell, substantially as set forth.

In testimony that I claim the foregoing I have hereunto set my hand, at Grand Rapids, in the county of Wood and State of Wisconsin, in the presence of two witnesses.

DANIEL J. ARPIN.
